UNITED STATES PATENT OFFICE.

BENJAMIN F. CUMMINGS, OF LOCUST GROVE, OKLAHOMA, ASSIGNOR OF ONE-HALF TO
CLYDE W. DAVIS, OF LOCUST GROVE, OKLAHOMA.

METALLIC TIE AND RAIL-FASTENER.

1,311,323.

Specification of Letters Patent. Patented July 29, 1919.

Application filed April 30, 1919. Serial No. 293,616.

To all whom it may concern:

Be it known that I, BENJAMIN F. CUMMINGS, a citizen of the United States, residing at Locust Grove, in the county of Mayes 5 and State of Oklahoma, have invented certain new and useful Improvements in Metallic Ties and Rail-Fasteners, of which the following is a specification, reference being had to the accompanying drawings.

10 This invention relates to an improved metallic tie and a rail fastener therefor, and a general object of the invention is to provide a device of this kind which is simple, efficient and practical in construction, and 15 may be manufactured for a small cost and installed on the roads at a reasonable profit, consistent with the construction herein shown.

A further object of the invention is the 20 provision of a metallic tie of this general character having base portions at its opposite ends and a thin central connecting part intermediate the end portions of the tie, the under faces of the end base parts being 25 countersunk or dished, so that portions of the roadbed or ballast may extend upwardly therein, thereby preventing displacement of the tie.

A further object of the invention is to 30 provide bracing means, such as webs or the like between the end base portions and the body of the tie, thereby reinforcing the body and the base portions relatively to each other.

35 A further object of the invention is to provide a tie having rail plate receiving recesses, into which rail plates are received in a dove-tail fashion, thereby not only preventing displacement of the rail plates but 40 also preventing displacement of the rails, the bases of which are removably supported on said plates, there being means consisting of keys to prevent movement of the rail plates in a direction of the rails.

45 A further object of the invention is to provide improved means for holding the keys in their receiving openings of the ties, in such wise as to permit the keys to be removed when desired, but while such keys 50 are in engagement with their openings the rail plates are held secure and against movement.

This particular construction of the tie may be equally as well employed in connection with switch rails, as well as in connec-

tion with oppositely arranged rails of a straight track.

A further object of the invention is to provide a tie, and rail fastening therefor, of such general character that it may be 60 easily removed, and replaced or a new tie inserted, without disturbing any other part of the road.

While the design and construction at present illustrated and set forth is deemed preferable, it is obvious that as a result of a reduction of the invention to a more practical form for commercial purposes, the invention may be susceptible of changes, and the right to these changes is claimed, provided they 70 are comprehended within the scope of what is claimed.

The invention comprises further features and combination of parts as will be herein-after set forth, shown in the drawings and 75 claimed.

In the drawings:

Figure 1 is a plan view of the improved tie and rail fastener therefor, showing a pair of rails mounted upon the rail plates, which 80 are arranged in their receiving recesses of the tie.

Fig. 2 is a sectional view on line 2—2 of Fig. 1, showing the rail plate in place, the key holding the plate in position and the lug 85 overhanging the base of the rail.

Fig. 3 is an enlarged detail view of the key.

Fig. 4 is an enlarged detail view of the rail plate.

Fig. 5 is a detail view of another rail plate, having its lugs arranged, especially adapting the same for location relative to the joint of a pair of rails, so that the lugs may overlie the fish plates.

Fig. 6 is an enlarged detail view of the tie.

Fig. 7 is a detail view transversely of one end of the tie.

Referring more especially to the drawings 100 1 designates a tie which may be constructed of any suitable material preferably metal. This tie at its ends is provided with bases 2, the under faces of which are countersunk or hollowed out as shown at 105 3 so that the roadbed or ballast may extend upwardly thereinto, to prevent displacement of the tie. These bases are reinforced or braced relatively to the body 4 of the tie by means of the webs 5. It is to be noted 110

that the central portion of the tie is in the form of a thin connecting web between the bases. This central connecting web is provided with several openings, in order to 5 lighten the tie and reduce the amount of metal to be used. Also, the body of the tie, that is between the webs, which brace between the body of the tie and the bases, is provided with openings to lighten the tie 10 and reduce the amount of metal forming the tie.

The body of the tie immediately above the bases and substantially centrally thereof is provided with transversely disposed 15 dove-tail recesses 7. In order to afford the construction of the recesses 7, the body of the tie is enlarged or is provided with laterally extending parts 8. These dove-tail recesses receive rail plates 9, the opposite 20 edges of which are beveled as shown at 10, to engage the beveled walls 11 of the recesses. Each rail plate on one edge is provided with a notch 12, and a lateral portion of each of the enlargements (which have the 25 dove-tail recesses) of the tie, is provided with an opening 13, with which the notch 12 registers, when the rail plate is in position. This opening 13 receives a key 14, which also engages the notch 12 of the rail 30 plate 9, thereby securing the rail plate in position and preventing movement of the plate in a direction with the rail. This key 35 at its lower end is provided with a spring extension 15. This spring extension is formed on the key, by forming a recess 16 in one edge of the key at its lower portion, and then bending the extension in an offset direction inclining downwardly from the key, as shown in the sectional view, Fig. 40 2. It is to be noted that by forming the recess 16 in the manner shown, this spring extension 15 may easily bend at a point indicated at 17 (which is adjacent the shoulder 45 18). Also when forming the recess 16, a shoulder 19 is formed near the lower end of the extension 15. The shoulder 19 is provided for the purpose of engaging under one of the lateral portions of the enlargement of the tie, as shown in Fig. 2, in order to lock the 50 key in position in the opening and in engagement with the notch 12. In order to employ the key, its spring end is inserted in the opening 13, and then driven home, and it is to be noted that as the key passes 55 through the opening 13, its spring extension will yield sufficiently to enable the key to reach home. However, when the key reaches home, the spring extension will assume its normal position, relatively to the 60 body of the key, and in this way the shoulder 19 will engage under one of the lateral portions of the enlargement of the tie, thereby preventing upward displacement of the key.

65 One of the rail plates 9 is provided with

lugs 20, which are positioned diagonally opposite each other and are designed to overlie the base 21 of the rail 22, thereby preventing lateral movement of the rail. It is obvious that the tie may be easily removed, without disturbing any other tie. 70 For instance, by applying pressure upon the spring extension of the key sufficiently to move the shoulder 19 out of the path of the lower part of one of the lateral portions of 75 the enlargement of the tie, and then applying a hand crow-bar under the head 23 of the key, the key may be extracted. The rail plate may then be moved along the rail, until it disengages from its recess of the tie. 80 The rail plate may be removed by applying sufficient pressure or hammer blows thereon. After the rail plate has been removed from engagement with the recess, a partial turn may be imparted thereto, and owing 85 to the diagonal positions of the lugs, the rail plate may be detached from the base of the rail. Then by jacking up the rail, the tie may be removed from thereunder. The other rail plate is provided with op- 90 positely arranged lugs 24, instead of being diagonal, and this construction of rail plate is especially adapted for use in connection with the rails where a joint occurs. For instance, the lugs of this particular rail plate 95 overlie the fish plates 25, which connect the adjacent ends 26 of the rails. In order to remove this latter rail plate, the key may be removed in the manner hereinbefore stated, then the fish plates removed by first remov- 100 ing their bolts, and then the rail plate may be removed until its lugs reach the end of the rail sufficiently to be free of the rail.

Also, the fish plates 25 may remain connected to the rails, when the rails 26 are to 105 be removed. For instance, the overhanging lugs 24 are spaced just far enough to permit the rails 26 and their fish plates 25, to pass between the lugs, the adjacent end of the overhanging parts of the lugs being 110 suitably spaced in order to prevent contact with the bolts (not shown) that usually fasten the fish plates to the rails, as the rails and the fish plates are inserted between the lugs. It is obvious that the rails and fish 115 plates 26 and 25 may be inserted in place without removing such bolts. (Not shown.)

The invention having been set forth, what is claimed as new and useful is:

1. The combination with a metallic tie 120 having the upper portion of its body provided with a rail plate receiving recess, that portion of the tie having said recess having a vertical opening, of a rail plate in said recess and provided with oppositely ar- 125 ranged lugs in engagement with the base of a rail, said rail plate having a notch in one edge thereof, and means extending through the opening and engaging said notch to secure the rail plate in position, 130

2. The combination with a metallic tie having the upper portion of its body provided with enlargements, each having a rail plate receiving recess, each enlargement having an opening, a rail plate engaging the recess and provided with a notch registering with the opening, said rail plate having diagonal opposite lugs to overlie the base of the rail, a member removably fixed in said opening and engaging the notch of the rail plate, thereby holding the plate in position.

3. The combination with a metallic tie, provided with bases at its opposite ends, said bases having their under faces countersunk, the body of the tie on its upper portion above the bases having enlargements, said enlargements having transverse dove-tail recesses, each of said enlargements having an opening, of a rail plate dove-tailed in said transverse recess and provided with a notch to register with the opening, said rail plate having opposite lugs to overlie the base of a rail, and a key wedged in said opening and engaging said notch, and means carried by the lower end of the key engag-

ing the under part of the enlargements to prevent upward movement of the key.

4. The combination with a metallic tie, having bases at its opposite ends, said bases being countersunk in their under faces, the body of the tie near its opposite ends above the bases having enlargements provided with transverse dove-tail recesses, said enlargements having openings, of rail plates dove-tailed in said recesses having notches; one of said rail plates having diagonally opposite lugs overlying the base of the rail, a key removably fixed in said opening and engaging the notch, the lower end of the key having a spring extension provided with a shoulder at its lower end, to engage under one side of the enlargement when the key is driven home.

In testimony whereof I hereunto affix my signature in the presence of two witnesses. 45

BENJAMIN F. CUMMINGS.
